CONSTRUCTION SURFACING SYSTEM

Harold P. Ford, Seattle, Wash.

Application September 5, 1936, Serial No. 99,616

5 Claims. (Cl. 72—116)

My invention relates to a construction surfacing system, and the general object of my invention is to provide thin sheet, lightweight, waterproof, weatherproof, fire-resistant, beautiful, permanent and low-cost building surfacing for roofs, walls, and other parts of existing or new construction, of wood, steel or other materials.

Present surfacing systems for construction are all subject to one or more of the following disadvantages and objections: high first cost, together with high cost of maintenance; rapid depreciation in value, making financing and refinancing difficult; constitute fire hazards, and permit large losses of life and property; not watertight, resulting in decay, corrosion and damage; are deficient in regard to security and permanence; lack enduring beauty and attractiveness.

The surfacing of buildings, especially on those faces exposed to the weather, is of great importance. Much could be written about the unsatisfactory building surfacing methods of the past, and of the present time. These methods are wasteful in the extreme, of both materials and labor, largely because of their lack of permanence. Financing and refinancing of construction is far more difficult than need be, because of the rapid depreciation in value of building construction; because of the lack of enduring attractiveness of buildings; because of the lack of live public interest in our archaic and faulty building methods; and because of the lack of financial faith in these methods.

My invention overcomes the objectionable features hereinbefore set forth, by providing a thin-sheet plaster base for surfacing of construction, which has as its base a thin watertight membrane of metal or metal alloy; which has a coating of weatherproof adhesive material to protect this membrane, and to securely bind to this metal membrane a weatherproof aggregate surface; which further has the aggregate particles pressed or rolled into the sheet, to cause pitting or roughening of the thin metal membrane, to secure excellent bonding of the aggregate surface to the membrane, and to provide for expansion and contraction in the membrane; or which further has a heat treatment to increase setting and bonding of the adhesive material; or which further has a coating of grout consisting of sand and cement bonded to the aggregate surface, for further protecting and weatherproofing both the adhesive material and the metal membrane, and to furnish a surface capable of permanently bonding on a beautiful plaster or stucco coat.

Watertightness and permanence are insured by the metal membrane and by the multiple protection of same. The coating of cement plaster, together with the mineral aggregate surface, effectively protect the bonding or adhesive coating, and, together with this weatherproof adhesive coating, protect the metal membrane. Bonding is further secured by rolling or pressing to cause roughness or pitting of the thin metal membrane. This ample protection insures durability which is essentially permanent. Weathering agencies cannot penetrate or damage this watertight durable sheet; and cannot damage any construction work surfaced by same.

Joints are, to a large extent, avoided, because of the large area covered by each sheet. Where joints are used, they are of a watertight and permanent nature. A variety of joints is possible, because of the thinness of the sheets. Joints are sealed by cement or weatherproof adhesive, to bond the rough lapping edges together, and are further secured by metal ties.

Enduring beauty of construction is made possible, at low cost. This material is adaptable to all angles and curvatures of surface, vertical or horizontal, outside or inside. It is ideal to receive, and to permanently bond, beautiful coats of cement plaster or stucco in a limitless number of finishes and color combinations. These finish coats will be permanently bonded on because of the weather resisting qualities of the mineral aggregates and cement; because of the excellent bonding of the weatherproof aggregates to the watertight metal membrane by the weatherproof adhesive; and because of the ample protection of both the weatherproof bonding material and the metal membrane.

The above mentioned general objects of my invention, together with others inherent in same, are attained in the manner illustrated in the following drawings, the same being preferred exemplary forms of my invention, thruout which drawings like reference numerals indicate like parts:

Fig. 1 is a vertical section thru a plant unit used for applying a weatherproof adhesive coating and a weatherproof aggregate surface to thin metal membrane sheets.

Figs. 2, 3 and 4 are typical sections, in any direction, somewhat magnified, showing several stages in the process of manufacture of watertight plasterbase thin-sheets.

Fig. 5 is a typical section, in any direction, at approximately full size, of a plasterbase sheet at

eral grains which fall between successive sheets.

In Fig. 2 I show a thin metal sheet with a coating of weatherproof adhesive to bond to the thin sheet particles 13 of fine weatherproof mineral aggregates, of varying size. After the adhesive hardens or sets this sheet could be used as a watertight weatherproof plasterbase. However it is preferable to get more positive bonding of the aggregate to the thin metal sheet. By 10 rolling the sheet shown in Fig. 2, under high unit pressure, we get the sheet shown in Fig. 3 in which pitting or indenting of the thin metal sheet is caused by the adhering spaced apart and staggered larger mineral grains on opposite sides 15 of the sheet, in connection with high pressure. This deformation of the thin metal sheet is preferred as it gives an intimate and close bond and large contact surface between the aggregate particles and the indented membrane, and provides for expansion and contraction in the metal sheet. It is preferred to apply pressure to the sheets in multiple, as by applying high unit pressure to stacks 11, shown in Fig. 1. In this manner deformation of the thin metal sheet is 20 produced similar to that shown in Fig. 3, because of high pressure applied to the stack in which thin metal sheets are alternately situated between rough layers of hard mineral aggregates. The sheets can remain in stack, subject to more 25 or less pressure, until the adhesive bonding coating hardens or sets. In this manner, simple plant is possible with large capacity, and an excellent product is the result, namely a thin pitted watertight metal membrane coated and 30 protected by a weatherproof adhesive coating which securely bonds to the pitted membrane a rough surface of fine weatherproof mineral aggregate.

The aggregates 13 used may be particles of 40 natural rock or minerals, or may be particles of other weatherproof solids; they may be more or less uniform in size or of varying sizes; they may consist of rounded grains, as fine or coarse sands, or may consist of rough particles as 45 crushed rock. Aggregates of larger sizes than those shown may be used; however, larger aggregates will cause thicker and heavier sheets, and will not permit as secure bonding to the metal membrane, as will the finer aggregates. In 50 case the weatherproof adhesive coating is applied hot to the thin sheets, it is preferable to have the mineral aggregates 13 in a heated condition when applied.

After the mineral aggregate surface has been 55 bonded securely to the thin metal membrane by the weatherproof adhesive coating, and after the adhesive has hardened or set, the resulting thin sheets may be used directly as a thin sheet surfacing material or plasterbase. However, it is preferred to apply a thin coating of weatherproof fine sand and cement mixture, as shown at 60 17 in Fig. 4. This thin coating fills the spaces between the adhering aggregate grains; prevents same from being abraded; and furnishes an excellent surface for bonding a plastercoat. After 65 this thin sand-cement coating has set, sheets are ready for use as a plasterbase.

A heat treatment may be used, after pressing 70 the thin sheets, to eliminate any light volatile materials from the adhesive coating, and to cause the adhesive material to harden and to adhere more firmly to the metal membrane; or to bond the weatherproof aggregates to the metal membrane by a baked-on adhesive coating.

In Fig. 5 plasterbase sheets 18 are shown, at approximately full size, ready for use. In the following described methods of surfacing with plasterbase sheets, same are referred to as 18. Similar uses are possible for sheets which have 5 not received the complete series of treatments as described for sheets 18.

In Fig. 6 I show plasterbase sheets 18 applied as a weatherproof watertight surface over existing or new wood wall or roof construction 19, 10 and secured to same by durable nails, drive screws or other metal ties 20 with a plastercoat 21 of cement plaster or stucco applied on the plasterbase. If desired, the finish plaster coat may be butt-ended as shown at 22 and marked like 15 shingles, shakes, slates or tiles. Plasterbase sheets 18 could be applied lapped like shingles or tiles, if desired.

It is apparent how there is no waste of plastering materials when plastering on these plasterbase sheets. Moreover, the operation of applying plastercoat to these sheets is very easy, and highly skilled workmen are not required. A thin priming coat is recommended prior to finish 20 plaster coat.

When plasterbase sheets 18 are secured to other construction by nails or drive screws 20, same should preferably have points dipped in weatherproof adhesive material before driving, to make nail holes watertight, to protect nail 30 or drive screw from corrosion, and to hold nail or drive screw securely in place.

In Fig. 7 I show plasterbase sheets 18 applied as a watertight weatherproofing surface over steel frame wall and roof construction 23 and secured to same by metal ties 24, with a plastercoat 21 of cement plaster or stucco. Fig. 7 also shows the use of lapped joints, thinly cemented, together with metal ties 25.

In Fig. 8 I show plasterbase sheets 18 applied as a form material, between which, on which or against which concrete 26 is poured. Sheets 18 serve as a watertight form surface during the pouring operation, and bond to the concrete as it hardens or sets. Plasterbase sheets 18 also give a secure bond to the plastered surface 21. In this application of plasterbase sheets 18, the concrete may consist of a cemented mixture of porous lightweight aggregates, in which case the combination will consist of a beautiful plastered 45 surface 21 bonded to a watertight metal membrane plasterbase 18, which is bonded to a porous heat-insulating concrete 26. Fig. 8 also shows the use of plasterbase sheets 18 as a watertight 50 roof or floor surface above concrete, being cemented down, and serving to bond a finished top surface. Fig. 8 also shows the use of sheets 18 as a watertight membrane within a mass of concrete, and bonded on both sides to the concrete.

In Fig. 9 I show sheets 18 applied as a plasterbase for interior or exterior surfaces, including floors, walls, ceilings and coves. In Fig. 10 I show sheets 18 applied as a plasterbase for interior or exterior convex or concave surfaces, wherein this material serves as a watertight base for attaching plastered surfaces 21. This thin-sheet plasterbase is specially suited for various 55 irregular plastered surfaces.

In Fig. 11 I show sheets 18 applied as a watertight metal membrane plasterbase against, or above, lightweight porous heat-insulating block construction 27, wherein sheets 18 form a watertight surface over or against the porous blocks 70 75

27, and are secured to blocks by metal ties 28 or to framework 29 supporting the blocks, by metal ties 30; thus forming a watertight metal membrane plasterbase in combination with a heat-insulating block backing, together with a plaster surface 21 permanently bonded to plasterbase.

In Fig. 12 I show sheets 18 applied as a surfacing over a framework of wood or metal, 31 and 32 respectively, with space between plasterbase 10 surfaces packed or filled with lightweight porous loose mineral filler 33, thus forming a watertight metal membrane plasterbase in combination with loose heat-insulating backing.

In Fig. 13 I show sheets 18 applied as a watertight plasterbase or coping over or against water-absorbing brick or masonry surfaces 34, with sheets 18 secured to same by metal ties 35, with plastered surfaces 21. A similar use is the application of sheets 18 over thin-walled hollow block 20 construction.

In Fig. 14 I show the application of sheets 18 as a watertight and protective encasement of wood 36 or steel 37 posts, columns, beams, and other structural members, with plaster coat 21.

In Fig. 15 I show a section of a structural angle 38 and of a thoroughly dry wood member 39, coated with weatherproof adhesive material, preferably emulsified bituminous material, by which a roughened surface of fine mineral aggregate 40 is caused to adhere to the structural member to produce a surface suitable for bonding plastercoat 21.

In Fig. 16 I show a preferred type of lap joint of sheets 18, wherein sheets 18 are applied against a wood surface 41; wherein sheets 18 are lapped as shown, together with cementing or adhesive material 42 applied between the sheets in the lap; wherein a large wire or small rod 43 extends continuously along the lapped joint and situated between the surface 41 and the underlying lapping edge, together with nails or drive screws 20 along edges of lapping sheets, each side of rod 43, thus to produce a crimping effect in the lapping edges, and positive sealing of the cemented joints.

In Fig. 17 I show the application of sheets 18 to the manufacture of posts, by bending sheets around a form, together with a plaster coat 21. The center may be filled with concrete 26.

In Figs. 18 and 19 I show a type of rolls for producing pitting or indenting of a thin metal membrane, wherein thinsheets 1 are passed between two rolls, as shown by arrows. Roll 44 is a hard surface roll having projections and depressions on its face. Roll 45 has a yielding surface, as of hard rubber. As a result of passing between rolls 44 and 45, thin sheet 1 is given a pitted surface as shown at 46. In Figs. 20 and 21 I show an alternate method of producing pitted sheets 46, in which both rolls have hard faces

together with intermeshing projections and depressions on faces.

In Fig. 22 I show pitted sheets 46 coated with fine weatherproof aggregate particles 13 bonded to the pitted sheets 46 by a weatherproof adhesive coating, to form a watertight plasterbase.

In Fig. 23 I show a thin metal sheet 1 bonded on both sides to fine weatherproof aggregate particles 13 by a weatherproof adhesive material. By pressing this sheet between hard surfaces a thin watertight plasterbase is formed, as shown in Fig. 24, wherein some of the aggregate particles are pushed into the thin metal membrane to form pitting or cupping of same, and thus the aggregates have large area of contact with, and secure bond to, the membrane.

Obviously, changes may be made in the form, dimensions and arrangement of the parts of my invention, without departing from the principle thereof; the above setting forth only a preferred form of embodiment.

I claim:

1. A new article of manufacture comprising a thin metallic membrane having irregular indentations disposed therein, an adhesive coating affixed to one side of the membrane, and a layer of aggregate bonded to the membrane by the adhesive coating, individual particles of the aggregate being intimately cupped within the indentations.

2. A device of the class described comprising a thin membrane, a plurality of indentations disposed upon the membrane, a primary coating of adhesive material spread upon the membrane, and a secondary coating of aggregate spread upon the coating of adhesive material, individual particles of said aggregate being cupped within said indentations.

3. A device of the class described comprising a metallic membrane, a plurality of indentations disposed upon the membrane, a primary coating of cementitious material spread upon the membrane, and a secondary coating of aggregate material disposed upon the primary coating of cementitious material, particles of said aggregate being recessed within said indentations.

4. A plasterbase comprising an indented metallic membrane having a foraminated cementitious coating affixed thereto, and particles of aggregate recessed within the indentations of the membrane and piercing the foramina of the coating.

5. A plasterbase comprising a thin metallic membrane having indentations disposed therein, a primary coating of cementitious material disposed upon the membrane, and a secondary coating of aggregate material intimately disposed upon the primary coating and matrixed within said indentations.

HAROLD P. FORD.
